UNITED STATES PATENT OFFICE.

GEORGE W. WALLACE, OF EAST ST. LOUIS, ILLINOIS.

APPARATUS FOR DISTILLING OIL.

Application filed May 20, 1922. Serial No. 562,500.

To all whom it may concern:

Be it known that I, GEORGE W. WALLACE, a citizen of the United States, residing at East St. Louis, Illinois, have invented a 5 certain new and useful Improvement in Apparatus for Distilling Oil, of which the following is a full, clear, and exact description, such as will enable others skilled in the art to which it appertains to make and use the 10 same.

This invention relates to an apparatus for cracking oils.

An object of this invention is to provide a pressure still for cracking oils that is more 15 efficient than the oil cracking stills now in general use, easier to control and also safer. Another object is to provide a pressure still for cracking oil that is equipped with an efficient means of novel construction for 20 continuously removing carbon from the heated surfaces of the still when the still is in operation, thus making it particularly adapted for cracking shale oil, owing to the 25 fact that considerable quantities of carbon are formed in cracking shale oil.

And still another object is to provide an oil cracking still which is of such construction that the carbon produced by the cracking operation is recovered in the form of a 30 soft, flocculent precipitate known commercially as "carbon black". Other objects and desirable features of my invention will be hereinafter pointed out.

To this end I have devised a process, 35 which, briefly stated, consists in distilling oil in a still under a pressure sufficient to keep the oil in a liquid state, causing the light hydrocarbons produced by said distilling operation to pass through a dephlegmator or fractionating column which is 40 maintained under approximately the same pressure as the still and when so arranged, conducting the light hydrocarbons from the dephlegmator through a condenser which is 45 maintained under approximately the same pressure as the dephlegmator and still, and subjecting the heavy hydrocarbons separated from the light hydrocarbons in the dephlegmator to a further cracking operation. The 50 temperature to which the oil is subjected in the still and the pressure that is maintained in the condenser, dephlegmator and still will vary according to the kind of oil being cracked. In practicing the process on 55 oils having normally boiling points of approximately 550 degrees to 650 degrees F.,

the oil in the still will be maintained at a temperature varying around 700° to 800° F. and sufficient pressure will be maintained in the still to keep the body of the oil in a 60 liquid condition at this temperature. The light hydrocarbons produced from the distillation of the oil in the still are then conducted to a dephlegmator or fractionating column, so as to cause the heavier hydrocarbons to be separated from the lighter hydrocarbons, the lighter hydrocarbons being conducted from the dephlegmator to a condenser and the heavier hydrocarbons being conducted from the dephlegmator back 70 to the still or to a separate still in which they are subjected to a further cracking operation. I am aware of the fact that it is old to crack or destructively distill oil under pressure in a still also that it is old 75 to then pass the light hydrocarbons thus formed through a condenser that is maintained at substantially the same pressure as the still, and conduct the light hydrocarbons produced by the cracking operation through 80 a dephlegmator and then through a condenser, either or both of which are maintained at substantially the same pressure as the still, and causing the heavy hydrocarbons that are separated from the light 85 hydrocarbons in the dephlegmator to be conducted back into a still, wherein they undergo further cracking. By handling the light hydrocarbons in this manner I obtain, 90 in one operation, practically a complete separation of that fraction of the oil from which motor fuel is refined, which, under the present practice, would require further refining to effect the separation of the fraction, which, when chemically treated and 95 redistilled, constitutes motor fuel or gasoline. Furthermore, I am able to return to the still the heavy hydrocarbons separated in the dephlegmator while said heavy hydrocarbons are in a heated state.

Various kinds of apparatus may be used in practicing my process, but I prefer to use an apparatus composed of a still of such design that the quantity of oil in the still at any given time per square foot of still heating surface is materially less than the amount of oil in the conventional oil cracking still, and provided with means for preventing carbon from caking on the heating surfaces of the still, a dephlegmator or fractionating column of any suitable type or kind connected with the still in such a man-

ner that the vapors evolved in the still will pass through said dephlegmator, means whereby the heavy hydrocarbons separated from the light hydrocarbons in said dephlegmator can be returned to the still or to one of a battery of stills for further cracking, a condenser of any suitable type or kind connected with the dephlegmator, means for maintaining the condenser, dephlegmator and still under the desired pressure and means for separating the permanent gases formed during the cracking operation from the liquid oils condensed in the condenser.

15 Figure 1 of the drawings is a diagrammatic view, illustrating an apparatus constructed in accordance with my invention for practicing my process.

Figure 1^a is a diagrammatic view, illustrating a slight change that can be made in said apparatus.

Figure 2 is a vertical longitudinal sectional view of the still and the furnace that is used for heating same.

25 Figure 3 is a front elevational view of the still proper.

Figure 4 is a detail vertical sectional view, illustrating a portion of one type of dephlegmator that may be used.

30 Figures 4^a and 4^b are similar views, illustrating other types of dephlegmators that may be used; and

Figure 5 is a perspective view, illustrating one type of condenser that may be used.

35 Referring to the drawings which illustrate the preferred form of my invention, A in Figure 1 designates an oil cracking still, B designates a dephlegmator or fractionating column, C designates a condenser and D designates a gas and liquid separating device connected with the outlet of said condenser. The oil that is to be cracked is preferably fed into the lower end of the still A through an oil supply pipe 1 and the gases and vapors that are evolved in the still are conducted from the upper end of the still through a pipe 2 that leads to the lower end of the dephlegmator B. The light hydrocarbons that are separated from

45 the heavy hydrocarbons in the dephlegmator are conducted from the upper end of the dephlegmator through a pipe 3 that leads to the condenser C and the heavy hydrocarbons are conducted from the dephlegmator through a pipe 4 that leads from the lower end of the dephlegmator.

50 The fixed gases produced in the cracking operation and the liquid oil that is condensed in the condenser C pass from the condenser through a pipe 5 into a suitable separating device D, wherein the gases are separated from the liquids, the gases escaping through a discharge pipe 6 leading from the upper end of the separating device D and

60 the liquids escaping through a liquid dis-

charge pipe 6^a leading from the lower end of said device. A valve 7 is provided for maintaining a practically uniform pressure in the condenser, dephlegmator and still, said valve 7 being arranged either in the 70 discharge pipe 5 leading from the condenser, or the fixed gas discharge pipe 6 leading from the separating device D. When the dephlegmator and condenser are to be maintained at a pressure different from the still pressure, the valve 7 may be arranged at any suitable place to produce the result.

Still.

The still A is preferably of the construction illustrated in Figures 2 and 3 and consists of two banks of tubes 8 and 9 arranged preferably in parallel relation, and preferably vertically disposed with one bank positioned in front of the other, an upper 80

header 10 consisting of a transversely-disposed drum connected to the upper ends of both of said banks of tubes and a lower header 11 consisting of a transversely-dis-

posed drum connected to the lower ends of 90 both of said banks of tubes, the tubes constituting each bank being spaced apart, as shown in Figure 3. Any suitable means

can be used for heating the tubes 8 and 9, but I prefer to arrange said tubes in a passageway 12 through which products of combustion travel from the combustion chamber 13 of a furnace, said passageway 12 being connected at its upper end to an uptake flue 14 that leads from the combustion chamber 100

of the furnace and being connected at its lower end to a stack flue 15, as shown in Figure 2. The passageway 12 and the flues 14 and 15 with which said passageway 105

communicates are preferably formed in masonry, and the upper and lower headers 10 and 11 of the still are arranged outside of the path of travel of the products of combustion.

Fuel oil, gas or any other suitable means 110 can be used to heat the still, and while I prefer to have the products of combustion enter the upper end of the passageway 12 and circulate downwardly through same longitudinally of the tubes 8 and 9 of the still, as indicated by the arrows in Figure 115

2, I do not wish it to be understood that it is essential that the still be heated in this particular manner, although this is the preferably way of heating the still, as it produces a still in which the rate of heat transfer is 120

materially higher than in the conventional oil cracking still, due to the fact that the hot gases first come in contact with the upper part of the still where the gases are most efficient for cracking the oil. 125

The oil to be cracked is preferably introduced into one end of the bottom header 11 of the still through the oil supply pipe 1, and when the still is in operation, the oil circulates rapidly through same and is main- 130

tained at substantially the level indicated by the dotted line α in Figure 2. Due to the fact that the oil circulates rapidly through the tubes of the still, it comes in contact with walls that are always maintained in a highly heated condition, thus insuring rapid heating of the oil, uniform mixture of the oil, and consequently, securing a uniform thermal reaction. As the upper header 10 is only partially filled with liquid oil, the upper portion of said header forms a vapor chamber wherein the products resulting from the cracking reaction are liberated and from which said products escape through the pipe 2 that leads to the dephlegmator. If the apparatus comprises a battery of stills, it is preferable to provide the vapor discharge pipe 2 of each still with an automatic safety check valve 16 that closes automatically when the pressure in a particular still becomes less than the pressure in the other stills and which opens automatically when the pressure in said still thereafter returns to normal. The upper header 10 of the still is also provided with a safety valve 17 that discharges into a reservoir or container (not shown) and which is of sufficient size to instantly relieve excessive pressure in the still. If desired, valves 18 and 19 can be arranged in the vapor discharge pipe 2 of the still on opposite sides of the automatic check valve 16, so as to enable repairs to be made on said automatic valve when the still is in operation.

In order to prevent carbon from caking on the interior of the tubes 8 and 9 and thus causing the tubes to burn out, means is provided for scraping off the carbon that collects on the interior of said tubes so that said carbon will fall downwardly to a point where it can be easily removed. In the form of my invention herein illustrated the means that is used for this purpose consists of endless chains 22 arranged in oppositely-disposed tubes of the front and rear banks of tubes 8 and 9, as shown in Figure 2, horizontally-disposed shafts 23 and 24 in the upper and lower headers 10 and 11, respectively, equipped with sheaves or other suitable wheels 25 around which the chains 22 travel, means such as a belt 26 for rotating one of said shafts, so as to cause the chains 22 to travel upwardly through the tubes of one bank and downwardly through the tubes of the other bank, and thus scrape off any carbon that deposits on the interior of said tubes and cause said carbon to fall downwardly into a collection chamber 27 that extends longitudinally of the bottom header 11 at the underside of same. If desired, the chains 22 can be operated in such a manner that the direction of movement of same is reversed automatically at stated intervals. While I prefer to provide the still

with two transversely-disposed banks of tubes, it is immaterial, so far as my broad idea is concerned, whether the still comprises two banks or more than two banks. In case the still is provided with four transversely-disposed banks of tubes, the horizontally-disposed shafts 23 and 24 in the headers can be provided with small sheaves or wheels, such as illustrated in Figure 2, that co-operate with endless chains which travel through pairs of tubes that are spaced close together and provided with larger sheaves or wheels that co-operate with endless chains which travel through pairs of tubes that are spaced farther apart. A hoe or other scraping device 28 that is arranged inside of the carbon collection chamber 27 is connected to an operating rod 29 that projects outwardly through a stuffing box 30 in one end of the carbon collection chamber 27, as shown in Figure 3, thereby permitting the carbon that drops downwardly into said chamber to be moved longitudinally of the chamber into a discharge pipe 31 that leads from one end of same, said carbon discharge pipe being preferably provided with a valve 32 that is normally closed. If desired, the drums that are used to form the upper and lower headers of the still may be provided in their end walls with manholes normally closed by covers (not shown), so as to facilitate the cleaning of the interior of the drums, and the soot that collects on the exterior of the tubes 8 and 9 can be removed from same by means of soot blowers or other devices that are commonly used for removing soot from the exterior of the tubes of a water tube boiler.

In a still of the construction above described the quantity of oil in the still at any given time per square foot of still heating surface is a small fraction of the amount of oil in an ordinary oil cracking still, thus materially reducing the fire hazard. Another thing that contributes to the safety of the still is the arrangement of the upper and lower headers 10 and 11 outside of the path of travel of the products of combustion used to heat the still and the arrangement of the tubes 8 and 9 in a passageway that communicates directly with the stack flue through which the products of combustion escape from the combustion chamber of the furnace. For example, even if one of the tubes should burn out, the oil that would escape from the ruptured tube would be carried up through the stack flue 15 without injury to the still. Owing to the fact that the tubes 8 and 9 of the still through which the oil circulates are equipped with carbon removing devices that travel longitudinally of said tubes, there is little liability of a tube of the still burning out, due to the caking of carbon on the interior of same. Consequently, the carbon removing means of the still also

materially reduces the fire hazard, as said means is of such design that it is a simple matter to keep the interior of the tubes clean and free from carbon deposits. Moreover, 5 as the carbon that is removed from the tubes falls down into a carbon collection chamber that is equipped with a hoe or other scraping device which can be operated from the exterior of said chamber, it is not necessary 10 to shut down the still at stated intervals so as to remove the carbon from same, as is necessary with the oil cracking stills now in general use. The chains that travel through the tubes of the still insure a rapid 15 circulation of the oil through the still in the direction in which the chains travel, and as said chains travel continuously through the tubes and rub against the interior of the tubes, it is practically impossible for carbon 20 to cake on the interior of the tubes. The result is that the carbon which is recovered from the collection chamber 27 is in the form of a soft, flocculent precipitate that is 25 commercially known as "carbon black".

Dephlegmator.

Various types of dephlegmators can be used for separating the light hydrocarbons from the heavy hydrocarbons so as to cause 30 only that fraction of the cracked oil which enters into the finished product to be supplied to the condenser and for causing the fractions which have not been sufficiently decomposed to be returned to the still or to a 35 separate re-cracking still. In Figure 4 of the drawings I have illustrated one type of dephlegmator that may be used which is composed of a vertically-disposed, cylindrical shell 34 provided with a funnel-shaped 40 lower portion 35 and having a number of horizontally-disposed trays *t* arranged inside of same, one above the other. Arranged inside of each of the trays *t* is a substantially inverted, cup-shaped baffle *b* that is provided with a depending tube *d* which projects 45 downwardly through the bottom of the tray, said tube having orifices *o* at the upper end of same and said baffle having a serrated or saw-toothed edge flange *o'* that is normally 50 submerged in the liquid oil in the tray. When the apparatus is in normal operation, the trays *t* will be filled with liquid oil that has been condensed from the vapors passing 55 from the still into the lower end of the dephlegmator. The vapor that enters the dephlegmator travels upwardly through the tube *d* on the baffle in the bottom tray, and upon reaching the upper end of said tube, escapes through the orifices *o* in same and 60 thence downwardly through the liquid oil in the tray, the uncondensed vapors escaping under the serrated flange on the baffle, and finally, escaping upwardly through the oil in the tray. After escaping from the bottom tray the uncondensed vapors pass successive-

ly through the various other trays of the dephlegmator, thereby ensuring a very complete separation of the light hydrocarbons from the heavy hydrocarbons. The light hydrocarbons pass from the upper end of the dephlegmator into the condenser, and the heavy liquid hydrocarbons that collect in the trays *t* escape therefrom through the orifices *o* in the tubes *d* and drain down to the heavy hydrocarbon return pipe leading from the 75 lower end of the dephlegmator.

The dephlegmator illustrated in Figure 4^a also comprises a vertically-disposed shell 35^a having numerous horizontally-disposed wooden trays *t'* arranged inside of same, one above the other and spaced apart so as to provide passageways up through which the uncondensed vapors travel, the heavy liquid hydrocarbons that collect in said trays over-flowing from same and draining down to the heavy hydrocarbon return pipe that leads from the lower end of the dephlegmator.

In Figure 4^b I have illustrated still another type of dephlegmator which consists of a vertically-disposed shell 35^b filled with small pieces of porcelain, fire brick, coke or any other suitable friction-producing material up through which the vapors circulate.

Irrespective of the particular type or kind of dephlegmator that is used, the dephlegmator will be provided at its lower end with a vapor inlet through which the vapors can enter from the vapor discharge pipe 2 of the still, a return pipe 4 through which the heavy hydrocarbons can be returned to the point where they are subjected to a further cracking operation, and an outlet pipe 3 leading from the upper end of same to the condenser. While I have herein illustrated the return pipe 4 as being connected to the oil supply of the still, this is not essential, for if desired, said return pipe could lead to the upper end of the still or to a separate re-cracking still, or through a suitable heat exchange device.

Condenser.

The particular type or kind of condenser that is used is also immaterial, the condenser shown in Figure 5 consisting of a container 40 filled with water and equipped with a pipe coil 41 having its inlet end connected to the discharge pipe 3 leading from the dephlegmator and its discharge end connected to the discharge pipe 5 which leads to the liquid and gas separating device D.

Operation.

To start the apparatus the still is filled with oil up to the approximate oil level indicated by the dotted line *x* in Figure 2 and a fire is started in the furnace that is combined with the still. When the pressure of the oil and the pressure in the still reaches

the desired point, the vapor in the vapor space in the upper header 10 of the still will escape from the still through the vapor pipe 2 to the dephlegmator. Until the dephlegmator is thoroughly warmed, practically all of the vapor entering same will be returned to the still or to the re-cracking still through the heavy hydrocarbon return pipe 4 that leads from the lower end of the dephlegmator. When the apparatus is thoroughly warmed up, liquid oil will begin to discharge from the condenser, the vapor and gases liberated in the still passing into the dephlegmator, wherein the light hydrocarbons are separated from the heavy hydrocarbons, and said light hydrocarbons thereafter admitted to the condenser and said heavy hydrocarbons thereafter returned to the point where they are subjected to further cracking. The valve 7, which may either be in the discharge pipe 5 leading from the condenser or the fixed gas discharge pipe 6 leading from the device D is adjusted so as to maintain the desired pressure in the various elements of the apparatus through which the vapors pass. As the light hydrocarbons are effectively separated from the heavy hydrocarbons in the dephlegmator, the liquid oil that is obtained in the condenser is a clean product that requires less chemical treatment to convert it into motor fuel than the product of the conventional oil cracking apparatus. Moreover, the heavy hydrocarbons that are recovered in the dephlegmator are returned for re-cracking while they are in a heated condition. From the foregoing it will be seen that my process insures a high yield of a clean product that can be refined into motor fuels with minimum trouble and expense, and the apparatus that I have devised for practicing my process is easy to control and is safer than the conventional oil cracking apparatus.

Having thus described my invention, what I claim as new and desire to secure by Letters Patent is:

1. A still for cracking oil, comprising a plurality of banks of tubes arranged in parallel relation and adapted to contain oil that is to be cracked, means for externally heating said tubes, headers communicating with the opposite ends of said tubes, endless carbon removing devices arranged in oppositely-disposed tubes of the respective banks, and means for moving said devices longitudinally of the tubes.
2. A still for cracking oil, comprising a plurality of banks of tubes arranged in parallel relation and adapted to contain oil that is to be cracked, means for externally heating said tubes, headers communicating with

the opposite ends of said tubes, endless carbon removing devices arranged in oppositely-disposed tubes of the respective banks, and shafts arranged longitudinally of said headers and provided with wheels around which said carbon removing devices travel.

3. A still for cracking oil, comprising a plurality of banks of tubes adapted to contain oil that is to be cracked, transversely-disposed headers at the ends of said tubes communicating with the tubes of the respective banks, a passageway in which said tubes are arranged, means for causing products of combustion to circulate through said passageway longitudinally of said tubes, endless chains arranged in oppositely-disposed tubes of the respective banks, sheaves or the like in said headers around which said chains travel, and means for actuating said chains so as to remove carbon that collects on the interior of said tubes.

4. A still for cracking oil, comprising a plurality of banks of tubes adapted to contain oil that is to be cracked, transversely-disposed headers at the ends of said tubes communicating with the tubes of the respective banks, a passageway in which said tubes are arranged, means for causing products of combustion to circulate through said passageway longitudinally of said tubes, endless chains arranged in oppositely-disposed tubes of the respective banks, sheaves or the like in said headers around which said chains travel, means for actuating said chains so as to remove carbon that collects on the interior of said tubes, a carbon collection chamber at the bottom side of one header, an outlet from said chamber, and means operable from the exterior of said chamber for discharging the carbon that collects in said chamber through said outlet.

5. A still for cracking oil, comprising a plurality of banks of tubes in which oil is to be cracked, means for externally heating said tubes, headers communicating with the opposite ends of said tubes, endless carbon removing devices arranged in oppositely-disposed tubes of the respective banks and means for moving said devices longitudinally of said tubes.

6. A still for cracking oil, comprising a plurality of banks of tubes in which the oil is to be cracked, means for externally heating said tubes, headers communicating with the opposite ends of said tubes, endless devices movable longitudinally thru said tubes to dislodge carbon from the inner surfaces thereof and convey the carbon from the tubes.

GEORGE W. WALLACE.
